UNITED STATES PATENT OFFICE.

HARRY MORRIS, OF CHICAGO, ILLINOIS.

DESIGN FOR A HAND BAG.

Application filed July 6, 1923. Serial No. 6,713. Term of patent 7 years.

To all whom it may concern:

Be it known that I, HARRY MORRIS, a citizen of the United States, residing at Chicago, county of Cook, State of Illinois, have invented a new, original, and ornamental Design for Hand Bags, of which the following is a specification, reference being had to the accompanying drawing, forming part thereof.

The figure is a front view of a hand bag showing my new design.

I claim:

The ornamental design for a hand bag as shown.

HARRY MORRIS.
